UNITED STATES PATENT OFFICE

154,520

DESIGN FOR A CAN PUNCTURING DEVICE

Lucille E. Weldon and George A. Peters, Sawyer,
Wis.; said Peters assignor to said Weldon

Application September 16, 1948, Serial No. 148,606

Term of patent 2½ years

(Cl. D22—2)

To all whom it may concern:

Be it known that we, Lucille E. Weldon and George A. Peters, citizens of the United States and residents of Sawyer, in the county of Door and State of Wisconsin, have invented a new, original, and ornamental Design for a Can Puncturing Device, of which the following is a specification, reference being had to the accompanying drawings, forming part thereof.

Fig. 1 represents a rear elevation of a can puncturing device embodying the features of our design.

Fig. 2 is a front elevation of the same.

Fig. 3 is a side elevation of said device.

Fig. 4 is an elevation showing the reverse side of the device; and

Fig. 5 is a plan view of the same.

We claim:

The ornamental design for a can puncturing device, as shown.

LUCILLE E. WELDON.
GEORGE A. PETERS.
